TWO-HAND CONTROL FOR PRESSES

George S. Baldwin, Cleveland Heights, Ohio, assignor to The American Laundry Machinery Company, Norwood, Ohio, a corporation of Ohio

Application January 11, 1935, Serial No. 1,334

6 Claims. (Cl. 68—9)

This invention relates to a pressing machine of the type used in laundry and garment work and more particularly to an improved control mechanism for a power operated pressing machine.

5 My improved control mechanism is applied to a pressing machine of the type having a pair of cooperating relatively movable pressing members, and power means for closing the press including motion transmitting mechanism having separable parts adapted to be coupled and uncoupled, these parts being normally urged toward uncoupled position and moved toward coupled position by a motor.

An object of the present invention is to supply novel control mechanism for such a press including spaced safety manuals requiring the use of two hands of an operator to hold the separable parts in coupled position until the press is safely closed.

20 Another object of my invention is to provide power means for closing a press of the class described having separable parts as above referred to, and control means for the press-closing motor biased in press-closing direction but latched in press-opening position. Two-hand control is provided for the coupling motor as above mentioned, and the control means for the press-closing motor is actuated by one of the manuals for the coupling motor.

25 Other objects and advantages of my invention will appear as the description proceeds and the essential features thereof will be summarized in the appended claims.

The drawing shows a side elevation partly in section of a pressing machine equipped with my improved control mechanism, the mechanism being shown in diagrammatic form so as to be more clearly understood.

30 My improved control mechanism is particularly applicable to a power operated pressing machine having motion transmitting mechanism between the power means and one of the pressing members for moving the same from its open to its closed position and into final pressure engagement with a cooperating member. The motion transmitting mechanism comprises separable parts which are normally uncoupled or in position ineffective to transmit power. These parts must be coupled or placed in effective position before the power means can effectively act to close the press. Many types of press structure are adapted to use the control mechanism described herein but I have chosen for illustrative purposes the pressing machine illustrated, described and claimed in Patent No.

1,747,879, granted February 18, 1930, to Robert C. Pauly. This press comprises a frame 10 on which is mounted a pressing bed 11 adapted to cooperate with a pressing head 12 which is carried by a head lever 13 pivotally mounted at 14 on a bracket of the frame. Toggle members 15 and 16 are movable toward straightened position for the purpose of moving the head lever about its pivot to bring the head into engagement with the bed. Toggle member 15 carries at its upper end a thrust rod 17 which is normally ineffective to move the head lever because it is uncoupled therefrom. To couple these parts a cap member 18 is pivotally mounted on the head lever at 19 and oscillatable about the pivot to place the portion 20 of the cap over the end 21 of thrust rod 17 so as to couple these two parts whereupon straightening of the toggles will actuate the head lever. Straightening of the toggle members is accomplished by power lever 22 pivotally mounted in the frame at 23 and connected by bracket 24 rigid with the power lever which carries a pin 25 which in turn engages in a slot 26 which is part of an angle lever 27 pivotally mounted in the frame at 28. The angle lever 25 is connected by link 29 with the knuckle of the toggles so that clockwise movement of power lever 22 produces counterclockwise movement of angle lever 27 which in turn pulls upon the link 29 to straighten the toggles. The parts are so arranged that when the toggles reach straightened position lever 22 exerts a powerful pry bar effect upon the straightened toggles, this effect being applied at the pivotal connection 30 between lever 22 and toggle member 16. Power means acts upon the lever 22 to close the press and the power means illustrated comprises a fluid actuated motor 31 having a cylinder 32 mounted on a trunnion 33 and equipped with a piston 34 whose piston rod 35 is pivotally connected at 36 with the forward end of the power lever. A spring 37 biases the head toward its open position. The above mechanism is substantially that shown in the Pauly patent referred to and further description may be found in the patent if desired.

35 My present invention provides power means for moving the cap member 18 to the position where the separable parts are coupled so as to effectively transmit power from the power means to the head lever. The power means shown comprises a fluid actuated motor 38 mounted on the head lever and having a cylinder 39 in which a piston 40 is adapted to reciprocate. The piston rod 41 is connected by a link 42 to an arm 43 which is

rigidly connected with the cap member. A spring 44 biases piston 40 to the right, as seen in the drawing, and thus serves to bias the cap member 18 toward its uncoupled position. Motive fluid 5 is supplied to motor 38 through a combined supply and exhaust conduit 45 which communicates with valve casings 46 and 47 which are connected in series by conduit 48, and valve casing 47 in turn communicates with a pressure fluid supply 10 49. In valve casing 46 is a normally closed inlet valve 46a and a normally open exhaust valve 46b mounted upon a common stem 46c for operation by a manual 46d. A spring 46e biases the valves toward their normal positions. Valve casing 47 15 is supplied with similar parts which are designated by similar suffixes.

Motive fluid is supplied to motor 31 through a common supply and exhaust conduit 50 which 20 communicates between cylinder 32 and valve casing 51 which houses a normally closed inlet valve 51a, which is in communication with the pressure fluid supply 49, and a normally open exhaust valve 51b which communicates by conduit 52 with the atmosphere. Valves 51a and 51b 25 are connected by their respective valve stems with a common actuator 53 which is so arranged that when one valve is closed the other is opened. The actuator 53 is pivotally mounted at 54 and is provided with an upwardly extending arm 55 30 which is normally biased toward fluid supply position by a spring 56. The arm 55, however, is latched in fluid exhaust position by a latch member 57 which is normally held against a stop member 58 by a spring 59. The latch 57 carries 35 a pin 60 which engages in a slot 61 in the link 62 which is pivotally connected at its opposite end at 63 with the manual 46d. The slot 61 provides a lost motion connection between link 62 and latch 57, while manual 46d is being actuated sufficiently to operate valves 46a and 46b. Thereafter, pin 60 is engaged by the end of link 62 to lift latch 57 and release the arm 55 whereupon spring 56 will move valves 51a and 51b to fluid supply position.

45 Suitable means is provided to move the actuator 53 in fluid exhaust direction at the close of a pressing operation. I have illustrated a treadle 64 connected by a rod 65 with a portion of actuator 53 and so arranged that, when the operator depresses the treadle, actuator 53 is oscillated in a counterclockwise direction as viewed in the drawing to close valve 51a and to open valve 51b and to latch arm 55 in engagement with the latch member 57.

50 The operation of the machine with the parts in the position shown in the drawing is as follows: The operator arranges the lay of the work on the bed 11 and actuates manuals 46d and 47d. The first result of such actuation is the closing of outlet valves 46b and 47b and the opening of inlet valves 46a and 47a. Pressure fluid then flows from supply 49 through valve 47a, conduit 48, valve 46a and conduit 45 to motor 38, thus oscillating the cap 18 in a clockwise direction about 55 its pivot and coupling the thrust rod 17 and the head lever 13. Both manuals 46d and 47d must be held in their actuated position until the press is finally closed because until the pressing members are in final pressure engagement the friction between parts 20 and 21 is insufficient to retain them in coupled position against the action of spring 44 tending to uncouple them. Further movement of manual 46d sufficient to take up the lost motion between pin 60 and slot 61 raises 60 latch 57, thus releasing arm 55 and permitting

spring 56 to move valves 51a and 51b to fluid supply position in which position they are held by the spring 56. When the press is fully closed, manuals 46d and 47d may be released. To open the press treadle 64 is depressed which returns 5 valves 51a and 51b to their fluid exhaust position shown in the drawing and latches them there. Pressure is relieved in cylinder 32 and spring 37 will open the press while simultaneously spring 44 moves the cap member 18 to its uncoupled 10 position.

What I claim is:

1. A pressing machine comprising cooperating relatively movable pressing members, a motor for producing final pressure between said members, 15 power transmitting mechanism between said motor and one of said members including separable parts adapted to be coupled or uncoupled and so arranged as to be capable of being coupled only when the press is in open position, means normally tending to uncouple said parts, a motor for coupling said parts, two-hand control means for said coupling motor, and means controlled by a part of said two-hand control means for energizing said final pressure motor. 25

2. In a pressing machine, a pair of cooperating relatively movable pressing members, power means for relatively moving said members to close the press and to cause final pressure engagement, control means for said power means, 30 said power means including motion transmitting mechanism having separable parts adapted to be coupled and uncoupled, means normally tending to uncouple said parts, a motor for coupling said parts, said parts being arranged to remain 35 coupled when the press is safely closed, and control means for said motor including two spaced safety manuals, one of said manuals having a connection with said control means for said power means for actuating the same. 40

3. In a pressing machine, a pair of cooperating relatively movable pressing members, power means for relatively moving said members to close the press and to cause final pressure engagement, control means for said power means 45 biased in press-closing direction, latch means for holding said control means in press-open position, said power means acting through motion transmitting mechanism having separable parts adapted to be coupled and uncoupled, means 50 normally tending to uncouple said parts, a motor for coupling said parts, said parts being arranged to be held in coupled position when the press is closed, and control means for said motor including two spaced safety manuals, one of 55 said manuals having an operative connection with said latch means for releasing the same.

4. In a pressing machine, a pair of cooperating relatively movable pressing members, power means for relatively moving said members to close the press and to cause final pressure engagement, control means for said power means biased 60 in press-closing direction, latch means for holding said control means in press-open position, said power means acting through motion transmitting mechanism having separable parts adapted to be coupled and uncoupled, means normally tending to uncouple said parts, a motor for coupling said parts, said parts being arranged to be held in coupled position when the press is closed, 70 and control means for said motor including two spaced safety manuals, one of said manuals having a lost motion connection with said latch means for releasing the same, the lost motion of said connection being taken up when said one 75.

manual performs its control function for said coupling motor.

5. In a pressing machine, cooperating relatively movable pressing members, a motor and motion transmitting mechanism for relatively moving said members from open to closed position for a pressing operation, a control member for said motor, means biasing said member toward press-closing-producing position, a latch 10 for holding said member in press-opening-producing position, a movable part having an operative connection with said motion transmitting mechanism, said part being movable from a disabling position, in which it renders impossible the closing of said press, to an enabling position in which it makes possible press closing movement of said motor and mechanism, said part being adapted to be held in enabling position by heavy friction between it and said mechanism 15 when the press is closed, means biasing said part to disabling position but ineffective against said heavy friction, power means for moving said

part to enabling position, and two spaced manuals for controlling said power means, one of said manuals having an operative connection for releasing said latch.

6. In a pressing machine, cooperating relatively movable pressing members, a motor and motion transmitting mechanism for causing relative movement of said members from open to closed position for a pressing operation, a movable part having an operative connection with 5 said mechanism, said part being movable from a disabling position in which it renders impossible the closing of said press to an enabling position in which it makes possible press closing movement, means biasing said part to disabling position, a motor for moving said part to enabling position, two-hand control means for said last named motor, and means controlled by a part of said two-hand control means for energizing said first named motor. 10 15
